Primary Examiner — Paula Allen Greene*(74) Attorney, Agent, or Firm* — Wood Herron & Evans LLP(57) **CLAIM**

The ornamental design for a microphone, as shown and described.

DESCRIPTION

FIG. 1 is a top front perspective view of a microphone in accordance with one embodiment of this invention;

FIG. 2 is a bottom rear perspective view of the microphone of FIG. 1;

FIG. 3 is a front elevational view of the microphone of FIG. 1;

FIG. 4 is a rear elevational view of the microphone of FIG. 1;

FIG. 5 is a right side elevational view of the microphone of FIG. 1;

FIG. 6 is a left side elevational view of the microphone of FIG. 1;

FIG. 7 is a bottom plan view of the microphone of FIG. 1; and,

FIG. 8 is a top plan view of the microphone of FIG. 1. The broken lines in these drawing views depict environment that forms no part of the claimed design.
